ATTORNEYS

UNITED STATES PATENT OFFICE

EDWARD ENGEL, OF BLOOMINGTON, ILLINOIS, ASSIGNOR TO MULLINS MANUFACTURING CORPORATION, OF SALEM, OHIO, A CORPORATION OF NEW YORK

WRINGER

Application filed December 2, 1931. Serial No. 578,453.

The object of my invention is to provide an improved mechanism for readily associating and dissociating the two coacting rollers of a wringer.

5 The accompanying drawing illustrates my invention in an embodiment suitable for ordinary household use.

Fig. 1 is a vertical axial section in partial side elevation;

10 Fig. 2 is an end elevation with a portion of the end walls of the base and cross-head broken away, and

Fig. 3 a fragmentary plan of one end of the base.

15 In the drawing 10 indicates a main frame or base, conveniently formed of sheet metal, and comprising hollow end standards 11, oppositely extending aprons 12, guard wings 13, and an intermediate trough 14 perforated 20 in its bottom.

Each end standard is provided, in a common manner, with a vertical guide, open at its upper end, for the reception and support of usual bearing blocks 16 of the lower roller 25 17 and for the reception of usual bearing blocks 18 of the upper roller 19. The above-described construction is well-known in the art and, in detail, may be varied through a wide range.

30 The upper end of each end standard 11 is open for the reception of mechanism, carried by the cross-head 20, now to be described.

The cross-head 20 is conveniently formed of sheet metal and so shaped and proportioned as to slightly sleeve over the upper open ends of the end standards 11.

Secured within the cross-head 20 near each corner is a bracket 21 into which is adjustably threaded a depending bolt 22 held in 40 desired axial adjustment by check nut 23. Sleeved upon each end pair of bolts 22 are the outwardly-projecting feet 24 of a bearing abutment yoke 25 formed to overlie one of the bearing blocks 18.

45 Journaled in each end of cross-head 20 is a short rock shaft 26 to which are nonrotatively secured the arms 27 of a U-shaped lever 28 the intermediate portion of which extends lengthwise of and overlies the cross-head 20.

50 Nonrotatively secured to the inner end of

each rock shaft 26 is a cam plate 30 provided with an inwardly projecting arcuate cam segment 31 adapted to underlie an anti-friction roll 32 journaled on a pin 33 carried by a cross bar 34 mounted in the upper end of standard 11. The bearing blocks 18 may be secured in the yokes 25 or said yokes 25 may be merely slidably engageable with said blocks.

55 Sleeved upon each bolt 22 and engaging the adjacent foot 24 is a compression spring 40 the upper end of which abuts a nut 41 on the bolt.

60 When the U-shaped lever is displaced to either extreme from its middle position, the adjacent ends of the arcuate cam flanges will lie free from the anti-friction rolls 32 and the cross-head with its yokes, springs, cams, rock shafts and U-shaped lever may be withdrawn upwardly from the base.

65 When the springs and yokes are reinserted in the base and the U-shaped lever is swung to its medial position, the cam flanges 31 will take under the anti-friction rolls 32 so as to tie the cross-bar to the base against upward 70 displacement. Proper adjustment of bolts 22 will correlate the parts so that when the cam flanges are thrown under the anti-friction rolls the upper roller 19 will either just rest upon the lower roller or will be put under 75 an initial compression by an initial compression of springs 40.

80 I claim as my invention:

1. A wringer comprising, a base having hollow end standards, a cooperating cross-head, bearing - abutment yokes slidably mounted at opposite ends of the cross-head and insertible into the end standards, springs interposed between the cross-head and abutment yokes, a lever straddling the cross-head with its ends journaled in the cross-head on an axis longitudinal of the cross-head, and means connected with said lever within the cross-head for separably engaging the base within the cross-head by angular movement 85 of the lever.

90 2. A wringer comprising, a base having hollow end standards, a cooperating cross-head, bearing abutment yokes slidably mounted at opposite ends of the cross-head and in- 100

sertible into the end standards, springs interposed between the cross-head and abutment yokes, a lever straddling the cross-head with its ends outside the opposite ends of the cross-head on an axis longitudinal of the cross-head, pivot shafts connected to said lever and projected into the opposite ends of the cross-head, a cam-plate carried by the inner end of each shaft, and cooperating projections carried by the base within the length of the cross-head and in positions to be respectively underlaid by portions of said cam-plates.

3. A wringer comprising a base having hollow end standards, a cooperating cross-head, two depending bolts carried at each end of the cross-head and insertible into the end standards, springs sleeved on said bolts, a bearing-abutment yoke sleeved on each end pair of bolts, a lever extending lengthwise of the cross-head, pivot shafts connected to said lever and projected into opposite ends of the cross-head, a cam-plate carried by the inner end of each shaft, and cooperating projections carried by the base within the length of the cross-head and in positions to be respectively underlaid by portions of said cam plates.

4. A wringer comprising a base having hollow end standards, a cooperating cross-head, two depending axially adjustable bolts carried at each end of the cross-head and insertible into the end standards, springs sleeved on said bolts, a bearing-abutment yoke sleeved on each end pair of bolts, a U-shaped lever straddling the cross-head lengthwise, pivot shafts connected to said lever and projected into opposite ends of the cross-head, a cam-plate carried by the inner end of each shaft, and cooperating projections carried by the base within the length of the cross-head and in positions to be respectively underlaid by portions of said cam plates.

In witness whereof, I have hereunto set my hand at Bloomington, Illinois, this 21st day of November, A. D. one thousand nine hundred and thirty-one.

EDWARD ENGEL.
